UNITED STATES PATENT OFFICE.

FREDERICK L. PORTE, OF UTICA, NEW YORK.

KNITTED FABRIC.

Application filed March 12, 1925. Serial No. 15,031.

My present invention relates to that class of knitted fabrics composed of a basic web and fleecing threads other than the basic web threads and which fleecing threads are placed 5 into the stitches of the basic web at all or certain of the courses of stitches, and knitted into such stitches.

The purpose of my invention is to provide an improved fabric of the type described and 10 one which is readily made, very durable in service and well adapted to allow the fabric to be used for many purposes.

A further purpose is to provide a fabric of the class described wherein the fleecing 15 threads are positively knitted into the basic fabric so that the fleecing threads will not work out and cannot be pulled out from the basic web, thus allowing the fabric to be used in many places of hard service where on previous 20 fabrics the fleecing threads would sooner or later be drawn out from the basic fabric either leaving the fabric entirely or hanging therefrom in long strings. On account of the permanency of the fleecing 25 threads of my fabric, the fabric is particularly well adapted for the hard usage incident to wash cloths, dish cloths, towels and the like.

A further purpose is to provide a fabric 30 wherein such knitted-in fleecing loops may be provided for either or both sides of the fabric and to allow such fleecing loops to be of as great a length as desired in order to give the fabric great weight or body such as is 35 desirable in wash cloths, towels, and fabric intended to be formed into wearing apparel.

A still further object of my invention is to provide a fabric wherein the fleecing loops 40 may be easily placed in a great variety of arrangements or relative positions such as having a course of fleecing loops at alternate courses of stitches upon the opposite sides of the fabric.

Further purposes and advantages of the invention will appear from the specification and claims herein.

Fig. 1 is a view on a greatly enlarged scale of the back or connecting thread surface of a portion of knitted fabric embodying my invention, and showing fleecing loops extending 50 from both the front and the back surfaces of the fabric.

Fig. 2 is a similar view of a piece of fabric provided with fleecing loops projecting only 55 from the back of the fabric.

Fig. 3 is a similar view of a piece of fabric

showing fleecing loops projecting only from the front or wale side of the fabric.

Referring to the drawings herein for a more particular description, it will be seen that I 60 have illustrated my invention by placing the fleecing loops upon a basic web commonly known as a simple plain web, such as is usually produced by a single series or circle of needles all knitting at each feed with one 65 thread. Ordinarily my invention will be used in connection with such a plain basic web; but the invention is not necessarily limited to such a web and certain of the claims herein are not limited to the basic fabric being 70 of such a plain web.

From the basic web thread 7 (indicated in the drawings as the clear white thread) there is knitted the basic web having vertical rows 75 of stitches 8 which form wales 17 on one surface of the fabric (hereinafter called for convenience and definiteness the front side of the fabric or the wale side of the fabric) with these stitches severally connected to the adjacent stitches in the same horizontal course 80 by the said basic web thread 7 extending horizontally as connecting threads 9 which connecting threads 9 are located on the other side of fabric (hereinafter called the back side of the fabric or the connecting 85 thread side of the fabric).

It will be understood that in the drawings the space between the two legs of a stitch loop and the space between adjacent stitch loops and also the space between successive 90 courses of stitches are shown greatly exaggerated relative to the size of the thread in order to more clearly illustrate the construction of the fabric. In the actual fabric the rows and courses of stitches are close to each other and 95 form with the knitted-in part of the fleecing threads a relatively compact fabric and the different series of fleecing loops extend from either or both sides of the fabric so close together as to project out from the body of the 1 fabric in the usual way of heavily fleeced fabric.

From a fleecing thread 10 there is formed along any given course of stitches a series of fleecing loops 11 projecting from the connecting side or back of the fabric.

In Figs. 1 and 2 this series of fleecing loops 11 are shown as present at alternate courses of the fabric. The thread to form these fleecing loops is passed through the upper part or eye of the loops in a course of the basic fabric as at course D and the two leg portions of

the knitted portion of the loop extend up to the next course as to the course E to have passed therethrough at the course E the beginning of another set of loops of the basic web or of 5 other fleecing loops. The outwardly projecting loop 11 is really the connecting thread of this fleecing thread extending from one row of stitches to adjacent and opposite rows of 10 stitches. It will be noticed particularly that 10 the fabric ends of this fleecing thread goes through the eye of the loop at one course of 15 stitches as D and then goes up to the next course of stitches as E to serve as part of the eye of the loop at such second course of 20 stitches to have the succeeding course of 25 stitches project therethrough. It will thus be seen that there is no possibility of the outwardly projecting fleecing loop 11 being pulled bodily from the fabric. Furthermore, 30 it is so thoroughly knitted into the two courses of stitches that the individual length of the projecting loop 11 is maintained against even the most severe usage.

In Fig. 1 the projecting loops 11 appear as 35 more or less regularly formed semi-circular inverted arches for the reason that the two threads going from the opposite ends of the loop to the body of the fabric go substantially to the center of adjacent rows of stitches making the arch have a diameter almost that of the distance from center to center of adjacent 40 rows of stitches. On the other hand these arch-shaped loops are really longer than they appear in the plan view drawings for the reason that these loops come up from the fabric at an appreciable angle. It will be understood that the loops may be of any desired length and that the angle they assume relative to the body of the fabric will vary according to the 45 relative size and character of the respective 50 yarns, the size of the needles and the general character of the fabric produced.

From a supplemental or fleecing thread 12 there is formed along any given course of 55 stitches a series of fleecing loops 13 projecting from the front or wale side of the fabric. In Figs. 1 and 3 of the drawings, these fleecing loops 13 are shown as present in alternate courses of the fabric and in the fabric as shown 60 in Fig. 1 these loops alternate with the other series of loops 11. This arrangement is simply one desirable arrangement of the loops 13 and of the series of loops 11 and 13 but is not the only or necessary arrangement within the 65 purview of my invention.

The threads forming these loops 13 are likewise knitted into the basic fabric by being passed through the upper part or eye of the loops in a course of the basic fabric as at 70 course C with the two leg portions of the knitted portion of the loop extending up to the next course as to the course D to have passed therethrough at the course D the beginning of another set of loops of the basic web in any 75 event and in most embodiments of my inven-

tion the beginning of other fleecing loops either of the series 11 or 13. These loops are really formed from the connecting threads of the fleecing thread 12 as they extend from one row of stitches to adjacent rows on each 80 side. These connecting threads start on the back or connecting thread side of the basic web and on the same side as the connecting thread loops 11 of the other supplementary thread 10. The loops 13 however, extend 85 through to the other or front or wale side of the basic fabric forming on that side the loops proper 13 which appear as relatively pointed loops with the intermediate portions 14 being the only part of the connecting threads left on 90 the back side of the fabric and with base portions 15 of this thread used to go through the fabric.

It will be noted that the sharply pointed appearance of these loops 13 is caused by these loops being pushed through the fabric with the two base portions 15 of each loop being crowded close together and held close together by reason of their being located between the adjacent leg portions of two adjacent stitches of the basic web. These loops 13 will also usually be longer relatively than shown in the plan view drawings for the reason that they extend from the body of the fabric at an appreciable angle thereto. It will be understood that this series of loops 13 may vary in length as desired according to the purpose of the fabric and that the angle of the loops will vary according to the character of the fabric. The loops of these series are especially inclined to 100 be at irregular angles to the body of the fabric and also to have the plane of the loops twisted to one side or the other incident to the two base portions 15 of each loop being so close together as to exert little influence to 105 hold the projecting loops 13 in any particular position.

What I claim as new and desire to secure by Letters Patent is:

1. In a knitted fabric, a basic web having 110 stitches arranged in longitudinally extending rows and laterally extending courses and supplemental yarns knitted into the stitches of the basic courses, the connecting threads of certain of said supplemental yarns extending outwardly in fleecing loops from the body of the fabric at certain courses on one side of the fabric and the connecting threads of the other supplemental yarns extending outwardly in fleecing loops from the body of the fabric at 115 certain courses on the other side of the fabric.

2. In a knitted fabric, a basic web having 120 stitches arranged in longitudinally extending rows and laterally extending courses and supplemental yarns knitted into the stitches of the basic courses with their connecting threads formed on one side of the fabric, the connecting threads of certain yarns extending outwardly in fleecing loops from the body of the fabric at certain courses on one side of the 125 fabric.

fabric and the connecting threads of the other supplemental yarns extending outwardly in fleecing loops from the body of the fabric at certain courses on the other side of the fabric.

5 3. In a knitted fabric, a basing fabric having its wales on one side and its connecting threads on the other side extending directly between opposite stitches in adjacent rows and supplemental yarns knitted into the 10 stitches of the basic fabric, the connecting threads of certain of said supplementary yarns extending out in loops from the wale side of the basic fabric and the connecting threads of the other supplementary yarns 15 extending out in loops from the connecting thread side of the basic fabric.

4. In a knitted fabric, a basic fabric having its wales on one side and its connecting threads on the other side extending directly 20 between opposite stitches in adjacent rows and supplemental yarns knitted into the stitches of certain of the courses with their connecting threads formed on the same side as the connecting threads of the basic web 25 and extending out in loops from the wale side of the basic fabric in certain of the courses, and from the connecting thread side of the basic fabric in certain other courses 30 of the fabric.

connecting threads of certain of said supplementary yarns extending out in loops from the wale side of the basic fabric in certain of the courses and with the connecting threads of the other supplementary yarns extending out in loops from the connecting thread side 35 of the basic fabric in certain other courses of the fabric.

5. In a knitted fabric, a basic fabric having its wales on one side and its connecting threads on the other side extending directly 40 between opposite stitches in adjacent rows and supplemental yarns knitted into the stitches of certain of the courses with their connecting threads formed on the same side as the connecting threads of the basic web 45 and extending out in loops from the wale side of the basic fabric in certain of the courses, and from the connecting thread side of the basic fabric in certain other courses of the fabric.

In witness whereof I have affixed my signature, this second day of February, 1925.

FREDERICK L. PORTE.
